UNITED STATES PATENT OFFICE.

HOSEA H. STRAIT, OF OVERLAND, MISSOURI.

PAPER-FEED GUIDE FOR PLATEN PRESSES.

1,407,100.

Specification of Letters Patent. Patented Feb. 21, 1922.

Application filed July 21, 1921. Serial No. 486,364.

To all whom it may concern:

Be it known that I, HOSEA H. STRAIT, a citizen of the United States of America, and a resident of Overland, in the county of St. Louis and State of Missouri, have invented certain new and useful Improvements in Paper-Feed Guides for Platen Presses, of which the following is a full, clear, and exact description, reference being had to the accompanying drawings, forming a part of this specification.

This invention relates to improvements in paper-feed guides for platen-presses, one of the objects being to produce a simple and inexpensive device of this kind adapted to be readily secured to a tympan to serve as a stop, or gage, for the sheets of paper delivered to the tympan.

A further object is to produce a simple feed guide having an adjustable tongue extending from its head, or abutment, so as to limit the upward motion of the edge of the paper engaging the abutment, the adjustable tongue being secured by the means whereby the device is attached to the tympan.

Fig. I is a top or plan view showing three of my guides mounted on a tympan.

Fig. II is an enlarged top or plan view of a guide embodying the features of this invention.

Fig. III is a side elevation showing the guide mounted on a tympan and platen, the latter being shown in section.

Fig. IV is a front elevation of the guide as it appears when in the locked condition shown by Figs. II and III.

Fig. V is a side elevation showing the guide as it appears when in its unlocked condition.

Fig. VI is a front elevation of the guide in its unlocked condition.

Fig. VII is a perspective view of one of the elements of the guide, showing the prongs which enter the tympan and the supporting arms to which certain levers are pivoted.

Fig. VIII is a perspective view of the locking lever.

Fig. IX is a top view of the gripping lever.

Fig. X is a side elevation of the gripping lever.

Fig. XI is a front elevation of the gripping lever.

A designates a tympan sheet adapted to be secured to the platen B (Fig. III) by means of a tympan-drawer C shown in Fig. I. A sheet of paper D, mounted on the tympan, is adapted to engage guides G which are secured to the tympan to determine the location of the paper to be printed. Each guide G includes a frame shown most clearly by Fig. VII and including a back flange 1, side arms 2 formed integral with 60 and extending forwardly from the ends of said back flange, and a pair of prongs 3 formed integral with and extending forwardly from the lower edge of the back flange. All of these parts may be made of 65 a single sheet of metal, as shown by Fig. VII. For a purpose to be hereafter pointed out, each side arm 2 is provided with a front perforation 4 near its front end and a rear perforation 5 near its rear end. A gripping 70 lever E is located between the side arms 2. Figs. IX, X and XI are detail views of this lever. It is preferably made of a single sheet of metal depressed at the middle as shown by Figs. III, V and X, and having 75 a downturned abutment flange 6 at its front end and curved pivot-forming extensions 7 near its rear end, said extensions being located in the rear perforations 5 in the side arms, so as to pivotally connect the gripping 80 lever to said side arms. Each extension 7 is preferably curved to conform to the wall of a perforation 5, as shown in Fig. V.

F designates a locking lever (Fig. VIII) 90 comprising a single sheet of metal located between the side arms 2 (Fig. II) and having pivot-forming extensions 8 projecting through the front perforations 4 in said side arms. These sheet metal extensions 8 95 are preferably curved to conform to the perforations 4 as shown by Figs. III and V. Locking lever F is also provided with a flange 9 adapted to extend downwardly as shown in Fig. III and engage the depressed 100 middle portion of the gripping lever E, so as to force the abutment flange 6 toward the prongs 3. The gripping lever E is provided with a tongue 10 adapted to be engaged by the extension 9, as shown in Fig. 105 V, so the lever F can be shifted from the position shown in Fig. III to the position shown in Fig. V, with the result of moving the abutment flange 6 away from the prongs 3. The device is thus unlocked to permit 110

removal of the prongs from the tympan sheet A.

To apply the device to a tympan sheet, the lever F is located in the position shown by Fig. V, and the prongs 3 are then inserted into the tympan sheet, as suggested by Fig. III, care being taken to accurately locate the abutment flange 6 in a predetermined position where it will serve as a stop for the sheets of paper delivered to the tympan, one of these sheets being indicated by D in Fig. I. After the prongs have been inserted into the tympan, the locking lever F is moved from the position shown by Fig. V to the position shown in Fig. III, thereby firmly gripping the tympan between the abutment flange 6 and the prongs 3. The prongs may be notched at 11, and the lower edge of abutment flange 6 will force portions of the tympan sheet into these notches to secure the device.

H designates a thin flexible sheet metal tongue located below the locking lever E and extending through a slot 12 in the abutment flange 6, said slot being shown most clearly in Figs. IX and XI. The flexible tongue H has a front portion inclined upwardly from the abutment flange 6 and the rear portion inclined downwardly from said abutment so as to lie between the prongs 3 and engage the bottom face of the gripping lever E. When the parts occupy positions shown by Fig. V, the tongue H can be adjusted longitudinally. This tongue serves as a stop for limiting the upward motion of the edges of the paper sheets engaging the abutment 6. The sheets are frequently slightly curled at their edges and when thrown against the abutment 6 they tend to pass over the entire device, but the tongue H prevents such displacement of the sheets.

The locking lever F has a downturned portion 13 (Figs. III and IV) in front of the upper portion of abutment 6, and an end flange 14 inclined upwardly from said downturned portion. The tongue H prevents the sheets of paper from entering between the abutment 6 and the downturned portion of the locking lever 13. At the junction of the end flange 14 and the downturned portion 13, a notch 15 is formed, said notch being open at the bottom to receive the tongue H. When the locking lever F is forced to its locking position (Fig. III) it engages the flexible tongue H and slightly bends the same at the abutment 6. The tongue H is then located in the slot 15 at the junction of the elements 13 and 14 so as to prevent lateral displacement of said tongue. The locking lever F therefore serves as means for preventing lateral motion of the tongue H, and it engages said tongue to bend it slightly, as shown in Fig. III. To prevent longitudinal displacement 65 of the tongue H, it is engaged by the lock-

ing lever F, as just pointed out, and a portion of this tongue lies directly between the depressed middle portion of the gripping lever E and the tympan sheet A. The prongs 3 are pressed to provide longitudinal ribs 16 on their top faces, and these ribs lie below portions of the tympan sheet A so as to elevate the same at a point below the depressed portion of the gripping lever E. So when the gripping lever is forced to its locking position (Fig. III) the tongue H will be gripped between the bottom of this depressed portion and the top of the tympan sheet A.

From the foregoing it will be understood that the tongue H is secured through the medium of the means for securing the guide, or gage, to the tympan, and that it is not necessary to provide any additional devices for holding the tongue in the position to which it is adjusted. This tongue can be very easily removed from the device whenever it would interfere with printing near margins of the sheets, and when the tongue is removed, the extended elements 13 and 14 on the locking lever F will tend to prevent the sheets from sliding from the device. However, these elements 13 and 14 (Fig. III) are not absolutely reliable, for the edges of said sheets may enter between the abutment 6 and the downturned portion 13. When the tongue H is in service, it positively prevents the edges of the sheets from entering between the portion 13 and abutment 6.

I claim:

1. A feed guide having a prong, a gripping member provided with an abutment movable toward said prong, a locking lever whereby said gripping member is forced toward said prong, said locking lever having a downturned portion in front of the upper portion of said abutment, and a tongue extending from said abutment at a point immediately below said downturned portion.

2. A feed guide having a prong, a gripping member provided with an abutment movable toward said prong, a locking lever whereby said gripping member is forced toward said prong, said locking lever having a downturned portion in front of the upper portion of said abutment, and a notch in the lower edge of said downturned portion, and a tongue passing through said abutment and extending from the front face thereof, said notch being open at the bottom to receive said tongue.

3. A feed guide provided with a support, a prong extending from said support, a gripping lever pivoted to said support and provided with a downturned abutment at one end located above and movable toward said prong, a locking lever pivoted to said support and engaging said gripping lever to force said abutment toward said prong, said

locking lever having a downturned portion in front of the upper portion of said abutment and an end flange inclined upwardly from said downturned portion, said locking lever also having a notch at the junction of said end flange and downturned portion, and a flexible tongue located below said locking lever and extending through said abutment, said notch being open at the bottom to receive said tongue.

4. A feed guide provided with a supporting frame having a back member, a pair of side arms extending forwardly from the ends of said back member, a pair of prongs extending forwardly from the lower edge of said back member and adapted to be inserted through a tympan sheet, a gripping lever mounted between and pivoted to said side arms, said gripping lever having a downturned abutment at its front end located above and movable toward said pair of prongs, a locking lever located between and pivoted to said side arms, said locking lever having a downturned portion adapted to engage said gripping lever to force said abutment toward said pair of prongs, said locking lever having a downturned portion in front of said abutment and an end flange inclined upwardly from said downturned portion, and a longitudinally adjustable flexible tongue located below said locking lever and extending through said abutment at a point below said downturned portion, said flexible tongue having a front portion inclined upwardly from said abutment and a rear portion inclined downwardly from said abutment so as to lie between said prongs and engage said gripping lever.

5. A feed guide provided with a supporting frame having a back member, a pair of side arms extending forwardly from the ends of said back member, a pair of prongs extending forwardly from the lower edge of said back member and adapted to be inserted through a tympan sheet, a gripping lever mounted between and pivoted to said side arms, said gripping lever having a downturned abutment at its front end located above and movable toward said pair of prongs, a locking lever located between and pivoted to said side arms, said locking lever having a downturned portion adapted to engage said gripping lever to force said abutment toward said pair of prongs, said locking lever having a downturned portion in front of said abutment and an end flange inclined upwardly from said downturned portion, and a longitudinally adjustable flexible tongue located below said locking

lever and extending through said abutment 60 at a point below said downturned portion, said flexible tongue having a front portion inclined upwardly from said abutment and a rear portion inclined downwardly from said abutment so as to lie between said 65 prongs and engage said gripping lever, and said prongs having ribs at their top faces to elevate the tympan sheet at a point below said gripping lever.

6. A feed guide comprising a sheet of 70 metal provided with a back flange, side arms formed integral with and extending forwardly from the ends of said back flange and a pair of prongs formed integral with and extending forwardly from the lower 75 edge of said back flange, each of said side arms having a front perforation near its front end and a rear perforation near its rear end, a gripping lever between said side arms, said gripping lever having pivot-forming extensions projecting into the rear perforations in said side arms and a downturned abutment flange at its front end, and a locking lever having pivot-forming extensions projecting into the front perforations 80 in said arms, said locking lever also having a downwardly extending portion adapted to engage the top of said gripping lever to force said abutment flange toward said prongs.

7. A feed guide comprising a sheet of 90 metal provided with a back flange, side arms formed integral with and extending forwardly from the ends of said back flange and a pair of prongs formed integral with and 95 extending forwardly from the lower edge of said back flange, each of said side arms having a front perforation near its front end and a rear perforation near its rear end, a gripping lever between said side arms, said 100 gripping lever being made of a single piece of sheet metal depressed at the middle and having a downturned abutment flange at its front end and curved pivot-forming extensions near its rear end, said extensions being 105 located in the rear perforations in said side arms, and a locking lever comprising a single sheet of metal located between said side arms and having pivot-forming extensions projecting into the front perforations in said 110 arms, said locking lever having an integral downwardly extending flange adapted to engage the depressed middle portion of said gripping lever to force said abutment flange toward said pair of prongs.

In testimony that I claim the foregoing I hereunto affix my signature.

HOSEA H. STRAIT.
